UNITED STATES PATENT OFFICE

JOHN JOSEPH SIPPEL, OF UPPER DARBY, PENNSYLVANIA, ASSIGNOR TO WICACO MACHINE CORPORATION, A CORPORATION OF PENNSYLVANIA

LOCKING MECHANISM FOR SWIFTS

Application filed January 2, 1930. Serial No. 418,137.

My invention relates to new and useful improvements in swifts for reeling machines, and more particularly to a mechanism for either quickly locking the swift in its reeling position, or readily unlocking the same, so that the yarn may be removed therefrom.

Still another object of the invention is to provide a quickly operable mechanism for locking the swift in its normal or working position, so that there will be no danger of the same collapsing during its winding and, at the same time, to so provide the locking mechanism that it is but the matter of a moment to pull a knob at the end of a shaft to thereby unlock the mechanism and cause the swift to collapse, so that the skeins may be quickly removed.

Still another object of the invention is to provide a locking mechanism for the swift, wherein all of the working parts of the locking mechanism of the swift are enclosed, so that there will be no parts projecting to interfere with the operator or to catch any of the yarn when removing the skeins.

Still another object of the invention is to provide a swift wherein there are two sets of brackets, each set being controlled (locked or collapsed) by the inward or outward movement of a central shaft or spindle, the respective sets of brackets being so connected to the spindles that the movement of a spindle in one direction will collapse its brackets or a movement of the spindle in the opposite direction will lock the brackets in their normal position.

With these and other objects in view, the invention consists in certain new and novel arrangements and combination of parts, as will be hereinafter more fully described and pointed out in the claims.

Referring now to the drawings showing a preferred embodiment,

Fig. 1 is a side elevation of a reeling swift, the brackets to the left being shown in their working or normal position and the brackets

to the right in the full lines being shown in their collapsed position, and the dotted lines showing the brackets in their normal or locked position;

Fig. 2 is an enlarged sectional view through one of the two oppositely located main spindles and showing the locking mechanism at the end of the spindle in its normal position;

Fig. 3 is a view similar to Fig. 2 but showing the locking mechanism after being unlocked, the dotted lines showing the links of the spider and brackets as being moved to their collapsed position;

Fig. 4 is an end view of the locking knob.

At the outset, it might be mentioned that the gist of the invention is the manner of connecting the brackets to a collapsible spider, the means for locking the spider in its normal position, and the manner in which the parts are formed and operated.

Referring now to Fig. 1, there is shown a portion of a frame 1, which may be part of a reeling machine, to which is secured a base or standard 2, in which there may be mounted a cross shaft 3 which will, in turn, be driven by a pulley 4, which shaft, through a worm 5, may operate the gear 6 and other parts which may operate or revolve the entire reeling swift. This central part or head so far described may be of any desired type and the various parts, such as clutches, releases and brakes, are not described, as they form no part of the present invention.

Still referring to Fig. 1, and glancing to the left half of the machine, there may be seen a spindle or shaft 7 over which there fits a partly hollow shaft 8, on the rear end of which is formed a non-collapsible spider 9 to which, in turn, is pivoted the arm 10 of a bracket 11, and likewise there may be seen a similar lower bracket 12 with its inner end or arm 13 pivoted, as at 14. It will be understood that there are generally about six of these brackets connected to each of the shafts. It might be mentioned here that the

same arrangement is carried out to the right of the swift and the parts are identical, so that a description of the one half of the machine, therefore, will be a description of the other.

5 These brackets may be hollow metal frames for the sake of strength and lightness and their outer faces will support the yarn or skeins, as will be readily understood.

10 Before describing further the manner in which these brackets are connected near their lower outer edges, a description of the collapsing and locking means for holding these brackets in their collapsed or normal position will be set forth.

15 Referring now more particularly to Figs. 2 and 3, the hollow shaft 8 and the spider 9 are secured by the bolts 15 to the revolving head. This spider 9 is formed with a plurality of bifurcated lugs 16 around its periphery which, in turn, respectively encase the heretofore mentioned lower arms 10 of the one bracket and the inner arm 18 of the opposite bracket. In the 25 same manner, all the rear lower arms of the various brackets will be pivotally supported, as will be clearly understood.

20 In the hollow shaft 8, there may be seen the bearing or supporting shaft 7 and it will be understood that the rotation of the shaft 8 and its integral spider will, of course, revolve the brackets connected therewith.

25 This shaft 8 near its outer end is slightly reduced, as at 17, and from a point near this reduced portion, it is cut-out, as at 18, for the reception of a form of locking spring 19 which is held in position by the pin 20. As may also be seen in Fig. 2, the cut-out portion 18 dips still further, as at 21, to provide 30 for the full downward movement of the outer end of the spring. This spring 19 is rounded on its lower surface at its inner end, as at 22, and snugly rests and fits within the cut-out portion 18, as may be readily seen.

35 The shaft 8, in turn, at its outer end is provided with another main sleeve 23, which slidily fits over the end of the shaft 8 and covers the cut-out portion 18 and the lock spring therein. The sleeve 23 is externally threaded, as at 24, and a small bearing collar 25 is threaded over the same. The inner end of the sleeve 23 has a plurality of peripherally spaced lugs 26 thereon, to which will be pivoted respectively links 27 which, in turn, receives a lug 28 formed on the lower surface of each bracket while a pivot 29 is passed through each link and the lug, so that the brackets may be collapsed, as will shortly be described.

40 These various toggle links connected to the respective brackets and connected to the lugs 26 on the sleeve 23 form what I term a collapsible spider, so that when this spider is moved outwardly and collapsed, the brackets 45 will also be collapsed, or their outer ends

tilted inwardly, so that the skeins may be quickly removed from the same.

45 Referring again to the end of the sleeve 23, there will be seen slidily fitted on the collar 25 the cored knob 30, which knob is recessed, 70 as at 31, so as to just nicely fit on the aforementioned collar 25.

50 The knob is reduced on its outer periphery, as at 32, and externally threaded, while threaded thereon is a small collar or cap 33 75 that has the rim 34 slidily engageable with the outer surface of the sleeve 23, so that when the knob 30 is moved to the left hand, the rim 34 contacts with a face of the collar 25.

55 Referring now for the moment again to 80 the spring 19, it will be seen that there is a trigger formation at its rear end, that is, there is a small seat 35 and an upstanding lug 36 that normally fits against the outer surface 25^a of the collar 25. When this lug 36 of the spring is up behind the collar 25, the sleeve 23 cannot move to the left or laterally on its shaft 8, because the spring, it will be remembered, is locked by the pin 20 to the main shaft 8 and, therefore, the shaft, link, and brackets connected therewith cannot collapse, but will be held in their locked or normal position, as may be seen from the left of Fig. 1.

60 Referring again to the locking knob 30, it 95 will be seen that the outer end is provided with a tapered bore 37, while the end of the spring 19 has the projecting finger 38 with a slight taper formed thereon; so that when this knob is pulled outwardly, the tapered 100 bore of the knob will force the spring finger downwardly to the position shown in Fig. 3 and thus lower the lug 36 from in front of the face 25^a of the collar 25. The knob having moved to the position shown in Fig. 3, the 105 rear collar or cap 33 or rather its rim 34 will now engage the rear face of the collar 25, so that the knob now on a further movement to the left will pull the sleeve 23 outwardly to thus collapse the various links 27, or, in other words, collapse the spider or break the link, and thus cause the brackets to tilt inwardly 110 at their outer ends, making it now possible to quickly remove the yarn.

65 In Fig. 1 to the right of the drawing, I 115 have shown in full lines the spider collapsed and the brackets in their unlocked position and the knob, of course, and its sleeve in its furthermore operative position.

70 When it is desired to again normalize and lock the brackets in their normal position for rotation, it is simply necessary to first force the locking knob inwardly so that the spring 19 will assume its normal position, that is, the lug 36 will again slip up in front of the face 25^a of the collar while the continued inward pressure on the knob will then force the sleeve 23 inwardly on its shaft 8 and again force the links 27 in an upright position to thus straighten the brackets and then lock 125 130

these links of the spider in their normal position.

The swift may again be operated and as long as the little knob is not pulled outwardly, the toggle and the brackets will remain in their normal and locked position.

It will be understood that although I have described one set of brackets and its locking mechanism, the parts will all be duplicated and there will be the two main shafts and their locking means, so that the brackets on either half of the machine may be readily collapsed or locked, as desired.

From the foregoing, it will be seen that I have provided a locking mechanism for a swift wherein the several brackets may be readily collapsed by simply grasping a little locking knob and giving it a preliminary pull and then a continued pull which, in turn, will collapse the spider or break the toggle and allow the brackets to collapse, while to set the brackets again in the normal position it is simply necessary to force the knob inwardly until its sleeve has returned to its innermost position, where the links will again be locked and will remain locked until the trigger mechanism is again released by an outward movement of the knob.

It will furthermore be seen that all of the locking mechanism is fully enclosed, so that there are no projections to interfere with the operator or to snag or catch any of the yarn when the skeins are being removed.

Many slight changes might be made without in any way departing from the spirit and scope of the invention.

Having thus described my invention, what I claim as new and desire to secure by Letters Patent is:

1. In a collapsible swift, a central shaft, brackets pivoted at the rear ends to said shaft, a sliding sleeve on said shaft and link mechanism radially connected to said brackets, a knob on said sleeve and a trigger on said shaft extending into said knob, said trigger normally positively locking the sleeve to prevent lateral movement of the sleeve and said knob cooperating with the trigger so that when said knob is initially operated the trigger will be released and the sleeve capable of sliding movement to thereby tilt said brackets.

2. A collapsible swift comprising a plurality of brackets, a central shaft, the said brackets pivoted at their rear to said shaft, a sliding sleeve on the end of said shaft provided with radial links extending therefrom and said links normally supporting the brackets in their operative position, a knob on said sleeve and a locking finger on said shaft cooperating with said knob to thereby prevent the collapse of the brackets, said knob capable of being moved outwardly on said sleeve to thereby operate the locking finger

and to permit the sleeve to be also laterally moved to thereby collapse the brackets.

3. In a reeling swift, a shaft, a slidable sleeve on the end of the shaft, brackets to be actuated by the movement of said sleeve, a latch finger fastened within the outer end of said shaft, the said sleeve fitting over said finger, a collar on said sleeve and a movable knob bearing on said collar, the outer end of said knob having a tapered bore and the latch finger having a taper and pressing against the wall of the bore, means on the knob for preventing the knob from being disengaged from the sleeve, the latch finger normally fitting in front of the said collar whereby an outward movement of said knob will force the latch finger out of its locked position to thereby permit the sleeve to be pulled outwardly.

4. In a reeling swift, a shaft, a slidable sleeve on said shaft, the end of the shaft provided with a recess and a latch finger fastened within said recess, the said latch finger having a tapered end extending beyond the end of the shaft and a collar threaded on the end of the sleeve and slidable on said collar, a cap on the rear of said knob and adapted to engage with said collar when the knob is pulled forwardly, said knob provided with a tapered bore at its end and the walls of the bore engaging the end of the latch finger, the latch finger having a seat normally engaging the collar on the sleeve whereby the sleeve is normally locked against movement on the shaft whereby a preliminary outward movement of the knob will release the latch finger from the collar and permit the slidable sleeve to be actuated.

5. A locking mechanism comprising a shaft and a movable sleeve on the end thereof, the end of the shaft having a recess and a latch finger fastened therein, the end of the finger extending beyond the end of the shaft, a collar on said sleeve and the latch finger normally engaging the collar to thereby prevent lateral movement of the sleeve, a knob on the sleeve and slidably engageable with the collar, the end of the knob having a tapered bore cooperating with the end of the spring finger whereby a preliminary outward movement of said knob will release said latch finger from the collar and permit said sleeve to be pulled outwardly on said shaft.

6. A locking mechanism for a collapsible swift comprising a shaft, a sleeve over the end of the shaft, brackets, and links connecting the sleeve with the brackets, a positive latch on the shaft and normally holding the sleeve against movement, a knob on the sleeve and cooperating with said latch whereby a preliminary outward movement of the knob will release the latch and permit the sleeve to be moved outwardly.

7. A locking mechanism to normally prevent the movement of a sleeve on a shaft

comprising, a shaft having a recess formed in its end, a latch finger fitting within said recess, a sleeve over said recess and finger and the end of the finger normally holding the sleeve from lateral movement, a knob slidably mounted on the sleeve, the knob and the end of the latch finger so formed that a preliminary movement of the knob will release the latch finger and permit the sleeve to be drawn outwardly.

In testimony whereof I affix my signature.
JOHN JOSEPH SIPPEL.
